LIQUID COOLING AND DISPENSING DEVICE

David H. Sniader, Chicago, Ill.

Application December 5, 1950, Serial No. 199,189

3 Claims. (Cl. 257—241)

1

This invention relates to a liquid cooling and dispensing device. More particularly it relates to a cooling and dispensing device wherein a plurality of coils are spirally wound about a reservoir tank in superposed relationship.

Cooling and dispensing devices which may be used for cooling and dispensing a variety of liquids consist, generally, of a reservoir casing or tank. A refrigerant coil is spirally wrapped around the tank in heat exchange relation and additional coils containing liquid to be cooled are wrapped around the refrigerant coil in somewhat superposed relation. The conventional construction is disclosed in the Smith Patent 2,063,002 patented December 1, 1936. In this construction it can be seen that the coils are disposed in superposed relation, but that a cross sectional view through the coils shows that they are positioned in somewhat of a pyramidal relation. In this position, during assembly, the coils are solder dipped and they are thus securely connected to each other and to the tank. In this construction therefore the reservoir tank is completely enveloped between the coils and the coils themselves are connected together in close unitary relation. This type of construction has been found to be unsafe from the point of contamination. Supposing for instance that a leak were to develop in the sides of the tank and simultaneously another leak were to develop in the refrigerant lines or in one of the liquid containing coils. Since the coils are held together in the unitary closed manner, such a leak might very well continue undetected for a considerable period of time with resulting contamination since refrigerant would mix with the liquid to be cooled. Thus in this conventional construction, intermingling or contamination of the liquids might easily occur and continue in an undetected manner. It is applicant's prime object therefore to provide an improved cooler and dispenser structure wherein any leaks can be instantly detected before damaging contamination can result.

Still another object is to provide a cooler having a plurality of spirally wound coils, wound on top of the other in superposed relation, the individual coil turns being vertically spaced and substantially apart with respect to each other to expose portions of the coils and a reservoir tank in a manner facilitating the detection of leaks.

A further object is to provide a cooler construction including a plurality of coils connected together in superposed relation and being laterally aligned, coil turns of the structure being vertically spaced and substantially apart with respect to each other.

Another object is the provision of a cooler including a tank having a plurality of spirally wound coils positioned around the tank, the coil turns being of varying diameters and being po-

2

sitioned in superposed laterally aligned vertically spaced and substantially apart relation.

These and further objects will become more readily apparent from a reading of the specification taken in connection with the accompanying drawing.

In the drawing:

Figure 1 is a side elevational view of a cooler and dispenser having portions broken away to better illustrate the invention.

Figure 2 is a cross sectional view in elevation through the cooler reservoir showing the embodiment of the invention.

Figure 3 is a detail view of a spacer member.

A cooling and dispensing device is generally designated by the reference character 10. The cooler 10 includes a reservoir tank 11 mounted on a support bracket 12. A tube 13 projects downwardly into the tank 11 adjacent the bottom thereof. The tube 13 may be in communication with a conduit 14 which will carry liquid to be dispensed. The cooler presently shown is especially adapted for soda fountains and in view of the large quantities of cold water that are needed, the tank 11 may be used as a cold water reservoir. It is readily apparent of course that the cooler is not limited to this use.

A coil section 15 is spirally wrapped around the tank in heat exchange relation therewith, the section 15 being connected to a branch line 15' which is adapted to connect to a source of refrigerant (not shown). The coil section 15 is thus a refrigerant expansion coil. A second coil section 16 is wrapped in spiral fashion around the coil section 15 as best shown in Figure 2. The section 16 is in communication with the section 15 and a branch 17 discharges the refrigerant to the source of refrigerant or refrigerating mechanism (not shown).

The refrigerant coils 15 and 16 include coil turns 18 and 19 respectively which are positioned in laterally aligned and spaced relation. A coil section 20 is spirally wound between the coils 15 and 16. The coil section 20 consists of coil turns 21 which are of lesser diameter than the turns 18 and 19 and are sandwiched in or disposed between the said coil turns in laterally aligned heat exchange relation. In soda fountain use, this smaller coil section 20 may contain soda water, a branch pipe 22 leading to a suitable source of soda water (not shown). A branch line 23 delivers the soda to a suitable line for dispensing.

A water coil 24 is in communication with the reservoir tank 11 as indicated at 25. The water coil 24 is spirally wound around the coil 16 in superposed relation, and includes coil turns 26 connected to the coil turns 19 of the coil 16 in contiguous heat exchange relation. A branch section 27 of the coil 24 leads to a source of water supply (not shown).

The cooling unit 10 is adapted to fit into a conventional dispensing arrangement in a well known manner and the means whereby the unit is connected to such a system need not be gone into in this disclosure. The invention as above indicated in the objects lies in the manner in which the spirally wound coils are positioned. A plurality of spacer members 28 are circumferentially positioned and vertically spaced for supporting the coil turns and to keep them in vertically spaced and substantially apart relation. As best shown, in Figure 2 it can be seen that the spacers 28 are so shaped that they will support the coil turns in laterally aligned superposed relation with a free vertical space between each of the coil turns so that portions of the tank 11 between the coil turns are exposed at all times. The spaces between the coil turns are designated by the reference character 29. The spacer members 28 may be of any suitable shape or design tending to maintain the vertically spaced and substantially apart relation of the coil turns.

The improvement thus shown consists of the spirally wound tubes which are maintained in superposed heat exchange relation with the coil turns laterally aligned in contiguous relation and vertically spaced and substantially apart with respect to each other.

As shown certain of the coils may be of varying diameters. It can be seen that when this assembly is solder dipped to fasten all the parts together with solder as indicated at 30, a sufficient free space will be maintained between the coil turns so that any leakages can immediately be detected before contamination can take place. Any leak would be immediately noticeable since the coil turns are separated and the leaking liquid would become immediately noticeable.

It can now be seen that an improved cooler and dispenser has been provided and it must be understood that changes may be made which do not depart from the spirit of the invention as disclosed, nor the scope thereof as defined in the appended claims.

What is claimed:

1. A liquid cooler and dispenser comprising a reservoir tank, a first coil of circular cross-section spirally wound around said tank, said first coil being adapted to connect to a source of refrigerant, a second coil of circular cross-section spirally wound around said first coil, said second coil being laterally spaced from said tank and engaging said first coil in superposed heat exchange relation, a third coil of circular cross-section spirally wound about said second coil and engaging said second coil in superposed heat exchange relation, a fourth coil of circular cross-section spirally wound about said third coil and engaging said third coil in superposed heat exchange relation, said third coil being in communication with said first coil and adapted to contain refrigerant, said second and fourth coils being adapted to contain liquid to be cooled, one of said second and fourth coils being connected and in communication with said reservoir tank, each of said coils including coil turns securely connected to each other in superposed heat exchange relation and laterally spaced with respect to said tank, said coil turns being vertically spaced substantially apart with respect to each other to provide open spaces between said turns and access to the outer surface of said tank, and a plurality of circumferentially disposed and vertically spaced spacer members, disposed between the coil turns and con-

nected to the tank, for maintaining the vertical spaced relation of said coil turns.

2. A liquid cooler and dispenser comprising a reservoir tank, a first refrigerant coil spirally wound around said tank for engaging the same in heat exchange relation, a plurality of coils spirally wound around said refrigerant coil in superposed relation laterally spaced from said tank, one of said coils being in communication with said refrigerant coil, another of said coils being adapted to contain liquid to be cooled and being disposed between the refrigerating coils and connected thereto in heat exchange relation, means connecting said liquid to be cooled coil to said tank for communication therewith, each of said coils including coil turns securely connected to each other in heat exchange relation, the coil turns being vertically spaced substantially apart with respect to each other to provide open spaces between said turns whereby portions of the tank are exposed between the turns, and a plurality of circumferentially disposed and vertically spaced spacer members connected to the tank and disposed between the coil turns for positioning the coil turns in the vertically spaced relation.

3. A liquid cooler and dispenser comprising a reservoir tank, a first coil of circular cross-section spirally wound around said tank, said first coil being adapted to connect to a source of refrigerant, a second coil of circular cross-section spirally wound around said first coil, said second coil being laterally spaced from said tank and engaging said first coil in superposed heat exchange relation, a third coil of circular cross-section spirally wound about said second coil and engaging said second coil in superposed heat exchange relation, a fourth coil of circular cross-section spirally wound about said third coil and engaging said third coil in superposed heat exchange relation, said third coil being in communication with said first coil and adapted to contain refrigerant, said second and fourth coils being of lesser cross-sectional diameter than said first and third coils for containing liquid to be cooled, one of said second and fourth coils being connected and in communication with said reservoir tank, each of said coils including coil turns securely connected to each other in superposed heat exchange relation and laterally spaced with respect to said tank, said coil turns being vertically spaced substantially apart with respect to each other to provide open spaces between said turns and access to the outer surface of said tank, a plurality of circumferentially disposed and vertically spaced spacer members, each of said spacer members extending laterally from said tank to said fourth coil and having narrow portions adapted to contact and vertically space equidistantly said first and third coils and having wide portions adapted to contact and vertically space equidistantly said second and fourth coils, said spacer members being disposed between the coil turns and connected to the tank for maintaining the vertical spaced relation of said coil turns.
